UNITED STATES PATENT OFFICE.

THEODORE D. FREESE AND CARL J. FREESE, OF ELYRIA, OHIO.

ANSWERING AND RECORDING TELEPHONE.

SPECIFICATION forming part of Letters Patent No. 745,342, dated December 1, 1903.

Application filed November 22, 1902. Serial No. 132,406. (No model.)

To all whom it may concern:

Be it known that we, THEODORE D. FREESE and CARL J. FREESE, both citizens of the United States, and residents of Elyria, in the county of Lorain and State of Ohio, have invented a new and Improved Answering and Recording Telephone, of which the following is a full, clear, and exact description.

Our invention relates to telephony, our more particular object being to provide automatic mechanism for answering calls in the absence of the operative in charge of the station and for automatically recording messages received from the line.

We will describe an answering and recording telephone embodying our invention and then point out the novel features in the appended claims.

Reference is to be had to the accompanying drawings, forming a part of this specification, in which similar characters of reference indicate corresponding parts in all the figures.

Figure 1 is a front elevation showing our device complete. Fig. 2 is a fragmentary elevation of the means for replacing the reproducer after the answering device has been used, the figure being an enlarged view, as from the right of Fig. 1. Fig. 3 is a section of the transmitter and the reproducer-tube connected thereto. Fig. 4 is a side elevation, partly in section, showing the principal portions of the recording device. Fig. 5 is an enlarged section of the reproducing mechanism taken at right angles to Fig. 3. Fig. 6 is a side elevation of the mechanism for producing records employed by the answering device, and Fig. 7 is a side elevation showing the mechanism for reproducing the record by the recording device.

The prominent parts of our device are as follows: first, a commutator A, controllable by the line, for throwing the apparatus into and out of action; second, magnetic mechanism B for actuating the commutator mechanism and for changing certain of the circuits; third, a transmitter C and connections for impressing communications upon the line; fourth, a phonograph D, normally provided with a reproducer; fifth, a trumpet E for conveying sound from the reproducer to the transmitter; sixth, a phonograph F, normally provided with a recording attach-

ment; seventh, an electric motor G for actuating the phonograph D; eighth, an electric motor H for actuating the phonograph F; 55 ninth, an electromagnetic device K, provided with suitable contacts for automatically shifting the current from the motor G to the motor H, and, tenth, batteries L for energizing the motors G and H successively. 60

A board 1 is provided with a shelf 2 for supporting the battery-jars 3, 4, and 5. Upon the upper portion of this board is a switch 6, connected with the main-line wires 7 8 and provided with stationary contacts 9 10. These 65 contacts are by wires 11 12 connected with a telephone 13, which is mounted on a board 14 and provided with an alarm-bell 15, a receiver 16, and divers other parts in the usual manner. 70

A contact 17 is connected by a wire 18 with a magnet 19, this magnet being connected by a wire 20 with magnets 21 and 22. From the magnet 22 a wire 23 is connected with an armature 24, this armature being mounted upon 75 a lever 25, journaled at 26 and provided with a pawl 27. The pawl engages a ratchet 28 upon the commutator 29, which is provided with insulating-sectors 30. The arrangement is such that when the magnet 19 draws the 80 armature 24 the pawl 27 moves the ratchet 28 a distance represented by one tooth, this movement of the commutator being just sufficient to shift the same into and out of circuit. A second movement of the armature 85 24 causes the commutator to move a distance represented by a second tooth, thereby virtually restoring the commutator to its original position in so far as its connection with the telephone-line is concerned. 90

A contact member 31 is mounted upon the armature 24 and is free to engage other contact members 32 32^a as the armature is attracted or released by the magnet 19. A wire 33 connects the contact member 32 with the 95 contact 34 of the switch, and a wire 35 connects the contact member 32^a with the receiver of the recording device F.

The recording device F consists of a telephonic receiver 36, provided with a magnet 100 36^a and with a diaphragm 36^b. Below the diaphragm is a sleeve 36^c, provided with another diaphragm 36^d, which may be of mica, metal, or any other preferred substance. Mounted

upon the diaphragm 36^d is a light bracket 36^e, which engages a tongue 36^f, provided with a jeweled point 36^g. The receiver 36 is connected by a wire 37 with the transmitter 38, as indicated more particularly in Fig. 1.

In connection with the phonograph D a trumpet or tube 39 is provided and is mounted somewhat loosely upon a bearing 40 and is provided with a bracket 41, having armatures 42 and 43 mounted thereupon. These parts depend from a shelf 44, as indicated more particularly in Fig. 2. The lower end of the trumpet 39 is provided with a diaphragm 45, upon which is mounted a plate 46, provided with a boss 47, this boss having a bearing 48, from which depends a lever 49, provided with a jeweled point 50. Mounted upon the trumpet is a threaded bearing 39^a, (see Fig. 5,) engaging a threaded shaft 39^b. (See Fig. 1.) This shaft is driven by a pulley c and belt 39^d. The lever 49 is journaled at 51, so as to have a comparatively free movement. (See Fig. 5.) The jeweled point 50 normally engages the revoluble record-cylinder 52 in the manner well known in phonography. The arrangement is such that when the phonograph just described is in action the sounds produced are carried upward by the trumpet E and actuate the transmitter C, thereby virtually causing the phonograph to talk upon the main line.

The recording-phonograph F is in some respects similar to the one just described. Its office, however, is to receive messages from the line and to record them upon the record-cylinder 63. The phonographs D and F are for the most part similar to the ordinary phonograph when used as a talking and recording apparatus, respectively. It is therefore deemed unnecessary to describe specifically the several parts of these phonographs except in as far as we have made alterations in the same.

Upon a frame 53 53 are mounted a number 45 of horizontal guide-rods 54 and the usual threaded shaft 55, carrying a slidible head 56, this head being provided with a lever 57, journaled upon the guide-rod 58 and having a finger 59, engaged by a thumb-lever 60. By 50 pulling down the thumb-lever the finger 59 is raised, thereby causing the lever 57 to bind upon a bracket 61, and thus depress the movable stem 62, so as to raise the point 36^g of the tongue 36^f out of engagement with the 55 cylinder 63 of the phonograph F.

In Fig. 6 is shown the means for charging the record-cylinder 52 with messages to be repeated automatically upon the line. Upon a diaphragm mounted within a boss 63^a is a 60 boss 64, connected with a lever 65, provided with a jeweled point 66, these last-mentioned parts being in many respects similar to the analogous parts already described. Upon the neck 67 of the boss 63^a is mounted a 65 speaking-tube 68, provided with a mouthpiece 69. When speech is uttered into the mouthpiece 69, the record-cylinder 52 being in

action, words are recorded in substantially the same manner as in ordinary phonography, the record thus produced containing predetermined messages to be given out upon the main line in answer to calls made from a distance.

In Fig. 7 is shown a device somewhat similar to that just described, but used for a different purpose—to wit, to reproduce the messages automatically recorded upon the record-cylinder 63. The diaphragm-box is shown at 70, the movable stem at 62, the boss at 73, the lever at 74, the jeweled point at 75, 80 the tube at 71, and the earpieces at 72.

The reproducer 45 is temporarily removed from the phonograph D and the apparatus shown in Fig. 6 substituted therefor when it is desired to charge the phonograph D with 85 messages. Similarly the apparatus shown in the upper portion of Fig. 7 is substituted for the receiver 36 when it is desired to listen to communications which have been automatically recorded from the line.

An electric motor 76 is connected with the phonograph D by means of a belt 77 and is provided with binding-posts 78 79. The binding-post 78 is connected with a contact 82, this contact normally engaging the armature 95 80 of the magnet 81. From the armature 80 a wire 88 leads to a contact-spring 87, which engages the commutator A. Another wire 83 is connected with the binding-screw 79 and with the jar 3 of the battery. A wire 85 is 100 connected with the battery-jar 5 and with a spring-contact 86, which also engages the commutator A. The magnet 81 is connected with the battery-jar 5 by a wire 84. From the magnet 81 a wire 89 leads to the lower one of 105 two contacts 90. The upper one of these contacts 90 is by means of a wire 91 connected with a switch 92, this switch being connected, by means of a wire 93, with another electric motor 94, provided with binding-posts 95 96. 110 From the lower post 96 a wire 97 leads to the battery-jar 3, as indicated in Fig. 1.

A belt 98 connects the motor H with the phonograph F. A contact 99 is mounted upon the trumpet 39 (see Fig. 1) for the purpose of 115 engaging the contact members 90. The movable parts of the phonograph D are mounted upon a bracket-frame 100.

The general operation of our device is as follows: When the operative is present, the 120 switch 6 is moved over to the right, thereby throwing the ordinary telephone 13 into circuit. If, however, the operative desires to leave his office or place of business, he moves the switch 6 to the left, as indicated in Fig. 1, and leaves such a record upon the cylinder 125 52 as will indicate his absence and give instructions to the subscriber calling him as to what course to pursue. For instance, he could charge the phonograph with a message 130 such as this: "Am going across the river; will not be back until four o'clock" or "Am temporarily out of the city; call No. 10." The operative before leaving the office may also

place a sensitive record upon the cylinder 63 for the purpose of receiving any communication which may be intended for him. In this event he so charges the phonograph D that the same will give full instructions to the calling subscriber. If the operative in leaving his office merely desires the reproducer D to operate, he opens the switch 92, thus preventing the contact members 99 90 from closing the circuit through the motor H. Suppose now that the phonograph D is charged with a message to be transmitted upon the line and that the phonograph F is charged with a sensitive blank. The switch being in the position indicated in Fig. 1 we will say that the call or signal for this office is flashed over the line in the usual manner. The signaling-current pursues the following circuit: wire 7, contact 34, wire 33, wire 35, receiver 36, wire 37, transmitter 38, wire 37^a, contact members 32^a and 31, armature 24, wire 23, magnets 22 and 21, wire 20, magnet 19, wire 18, contact 17, and line-wire 8. This energizes the magnet 19, causing the contact member 31 to disengage the contact member 32^a and at practically the same instant to engage the contact member 32. The armature is retracted by the spring 24^a. This movement of the armature 24 in consequence of the pull of the magnet 19 causes the pawl 27 to move the commutator, as above described, into the position indicated in Fig. 1, thereby enabling the contacts 86 87 to engage the metallic portion 29 of the commutator. While the armature 24 is thus raised, the current pursues the following course: line-wire 7, contact 34, wire 33, contact members 32 and 31, armature 24, wire 23, magnets 22 and 21, wire 20, magnet 19, wire 18, contact 17, and line-wire 8. A circuit is therefore completed through the magnet 19 whether the armature 24 be in its uppermost or lowermost position. The signaling-current having ceased, the armature drops downward, so that the contact member 31 again engages the contact member 32^a, completing the circuit first described, this circuit being through both the receiver 36 of the phonograph F and the transmitter C. The movement of the commutator incidental to the raising and lowering of the armature 24 establishes the following circuit: battery-jar 5, wire 85, brush 86, commutator member 29, brush 87, wire 88, armature 80, contact 82, binding-post 78, motor 76, binding-post 79, and wire 83 to battery-jar 3, thus completing the circuit through the motor G. The motor being thus energized drives the phonograph D and causes the reproducer 45 to deliver its message automatically through the trumpet 39 and funnel 38^a into the transmitter 38. The distant operative thereupon hears the message which has been charged into the phonograph D and learns therefrom what course to pursue. If, for instance, he is to give a verbal message in return, he waits until the phonograph D has finished its work and then delivers his message as if talking to an individual. The phonograph D will continue to run until the contact member 99 engages the contact members 90, thereby completing the following shunt-circuit: battery-jar 5, wire 84, magnet 81, wire 89, contacts 90 99, wire 91, switch 92, wire 93, binding-posts 95 95 of motor H, and wire 97 to battery-jar 3. This shunt-circuit energizes the magnet 81, causing it to draw the armature 80, and thus break the contact between this armature and the member 82, thereby stopping the motor G and throwing all of the current into the motor H through the circuit just traced. The motor H being thus energized actuates the photographic recorder F, causing the record-disk 63 to register the message from the distant operative. The absent operative for the office we are describing now returns, removes the receiver 36, places the apparatus shown in the upper portion of Fig. 6 instead thereof, and listens to the message which has come during his absence.

As will be seen in Fig. 2, the magnet 21 is placed a little to one side of and somewhat in front of the magnet 22. It will be understood that when the magnets 21 22 are energized by the signaling-current, as above described, the trumpet 39 is drawn to the right from the view-point in Fig. 1 by means of the magnet 21 and at the same time is moved laterally so that the reproducer 45 clears the surface of the cylinder 52, this latter movement being effected by means of simultaneous action of the smaller magnet 22. For the sake of clearness it may be well to look at Fig. 2 and imagine this view to be presented by a person standing at the right of Fig. 1. The signal from the distant operative, therefore, has the effect of placing the reproducer 45 at the right of the cylinder 52, so as to start the phonograph D at the beginning of its message.

The different operatives or subscribers, knowing the nature of the apparatus above described, will so transmit their messages that the same will be recorded at the proper instant—to wit, while the cylinder 63 is in motion. To do this, it is desirable for the operative at a distance to wait until the phonograph D has finished its message and the shifting mechanism K has thrown the motor G out of circuit and the motor H into circuit. We do not limit ourselves to the several particular types of parts shown and described; neither do we limit ourselves to the apparatus as used in connection with an ordinary telephone. Obviously the telephone shown in Fig. 1 may be disconnected, and our invention may be used by itself.

Various modifications and uses of our apparatus will suggest themselves to persons skilled in the art.

Having thus described our invention, we claim as new and desire to secure by Letters Patent—

1. An answering and recording telephone, including a telephone-line, a telephone-trans-

- mitter connected therewith, a phonographic reproducer connected with said transmitter for uttering speech thereinto, and mechanism connected with said line and controllable thereby for throwing said transmitter and said phonographic reproducer into action relatively to said line, and means controlled by the reproducer for throwing the same out of action.
10. 2. An answering and recording telephone, including a telephone-line, mechanism for automatically transmitting speech upon the same, a motor for actuating said mechanism, mechanism connected with said telephone-line for starting said motor, and means for stopping the motor and controlled by the automatic transmitting mechanism.
15. 3. An answering and recording telephone, including a telephone-line, mechanism for automatically impressing communications upon the same, a motor for actuating said mechanism, a source of electricity for energizing said motor, electric connections controllable by said line for starting said motor, and means controlled by said mechanism for stopping the motor.
20. 4. An answering and recording telephone, comprising a telephone-line, an answering device for automatically impressing communications upon the same, an automatic recording mechanism for registering communications from said line, independent motors for actuating said answering device and said recording mechanism, and means for automatically stopping one of said motors and starting the other.
25. 5. An answering and recording telephone comprising a telephone-line, an answering device for automatically impressing communications upon the line, an automatic recording mechanism for registering communications from said line, an electric motor for actuating the said recording mechanism, open-circuit wiring connected with said motor and provided with a contact member, and a contact member connected with the said answering device and controllable thereby for closing said open circuit.
30. 6. An answering and recording telephone comprising a telephone-line, a transmitter connected therewith, a phonograph-reproducer connected with said transmitter, means for actuating said reproducer, a recording-phonograph for registering communications from said line, an electric motor for actuating said recording-phonograph, open-circuit wiring connected with said motor and provided with a contact member, and a contact member connected with said reproducer, for closing said open circuit.
35. 7. An answering and recording telephone, comprising a telephone-line, an answering device for automatically impressing communications upon the same, automatic recording mechanism for registering communications received from said line, automatic motors for actuating said answering device and said re-

cording mechanism, respectively, means for energizing said motors, and an automatic shifting device for opening the circuit of one of said motors and closing that of the other.

8. An answering and recording telephone, comprising a telephone-line, an answering device for automatically impressing communications upon the same, automatic recording mechanism for registering communications received from said line, electric motors for actuating said answering device and said recording mechanism respectively, means for energizing said motors, an automatic shifting device for opening the circuit of one of said motors and closing that of the other, and means controllable by said line for actuating said shifting device.

9. An answering and recording telephone, comprising a telephone-line, a transmitter connected therewith, a phonograph-reproducer connected with said transmitter, a recording-phonograph for registering communications received from said line, electric motors for actuating said phonograph-reproducer and said recording-phonograph respectively, and automatic mechanism for opening the circuit of one of said motors and closing that of the other as set forth.

10. An answering and recording telephone including a telephone-line, a recording-phonograph for registering communications received from said line, the said recording-phonograph comprising a record-cylinder, a telephone-receiver having a magnet and a diaphragm, a sleeve below the diaphragm and provided with a second diaphragm, a bracket mounted upon the latter diaphragm, a tongue engaged by said bracket and formed with a point for recording on the record-cylinder, means for raising the point of the tongue out of engagement with the record-cylinder, and mechanism connected with said line and controlled therefrom for actuating said recording-phonograph.

11. An answering and recording telephone, comprising a telephone-line, an answering device for automatically impressing communications upon the same, an automatic recording mechanism for registering communications from said line, electric motors for actuating said answering device and said recording mechanism respectively, open-circuit wiring connected with said motors, an electromagnet having its armature in the circuit of the motor of the answering device and its coil in the circuit of the motor for the recording mechanism, means controlled by the telephone-line for closing the circuit through the wiring for the motor of the answering device and a contact member connected with and controllable by the answering device for closing the circuit of the motor for the recording mechanism, the closure of the latter circuit moving the said armature to open the circuit of the motor for the answering device.

12. An answering and recording telephone, including a telephone-line, a transmitter con-

- 5 nected therewith, a phonograph-reproducer connected with said transmitter, said reproducer being provided with a revolute member and with a stylus movable relatively thereto, electromagnets connected with the line, the armature of said magnets being connected with the stylus and adapted when attracted to place said stylus in a predetermined position relatively to said revolute member to start the reproducer at the beginning of the message, and means, controllable by said line, for actuating said reproducer.
- 10 13. An answering and recording telephone including a telephone-line, a telephone-transmitter connected therewith, a phonographic reproducer connected with said transmitter, said reproducer being provided with a revolute member and with a stylus movable relatively thereto, a trumpet carrying said stylus and connected with the transmitter, armatures carried by said trumpet, and electromagnets controlled by said line and arranged to attract said armatures to place said stylus 15 in a predetermined position relatively to said revolute member, and means controllable by said line for actuating said reproducer.
14. An answering and recording telephone, comprising a telephone-line, a transmitter connected therewith, a phonographic reproducer connected with said transmitter, said reproducer being provided with a revolute member and with a stylus movable relatively thereto, magnetic mechanism, controllable by 20 said line, for placing said stylus in a predetermined position relatively to said revolute member, means for actuating said reproducer, a recording-phonograph for registering communication from said line, an electric motor for actuating said recording-phonograph, open-circuit wiring connected with said motor and provided with a contact member, another contact member connected with said reproducer and controllable thereby for closing 25 said open circuit, and a source of electricity connected with said wiring for energizing said motor.
15. An answering and recording telephone, comprising a telephone-line, phonographic
- 50 mechanism disposed adjacent thereto and normally disconnected therefrom, electric mechanism for actuating said phonographic mechanism, a magnet-controlled commutator connected with said line for connecting the same with said phonographic mechanism and for disconnecting the same therefrom, a motor for driving the phonographic mechanism and brought into action by the movement of the commutator, and means controlled by the phonographic mechanism for stopping the motor. 55
16. An answering and recording telephone including a telephone-line, phonographic mechanism comprising a record-cylinder and a telephone-receiver provided with means for recording on said record-cylinder, an electric 60 motor for actuating the record-cylinder, a normally open electric circuit for said motor, a commutator, mechanism controlled by the commutator for closing the circuit through the motor, an electromagnet connected with 65 the line, a connection between the armature of the magnet and the commutator to move the same, and a contact member on said armature for completing the circuit through the telephone-receiver.
- 70 17. An answering and recording telephone, comprising a telephone-line, an answering device for automatically impressing communications upon said line, an automatic recording mechanism for registering communications received from the line, electric motors for actuating said answering device and said recording mechanism respectively, an electromagnet connected with the telephone-line, a commutator controlled by said magnet for 75 closing the circuit through the motor of the answering device, and means controlled by the answering device for closing the circuit through the motor for the recording mechanism.
- 80 90 In testimony whereof we have signed our names to this specification in the presence of two subscribing witnesses.
